PRINTING MECHANISM FOR TYPEWRITING MACHINES

Frank H. Trego, New York, N. Y., assignor, by mesne assignments, to Ralph C. Coxhead Corporation, New York, N. Y., a corporation of Delaware

Application November 9, 1929, Serial No. 405,878

2 Claims. (Cl. 197—49)

This invention relates to typewriting machines and more particularly to improvements in printing mechanism therefor.

In the Vari typer writing machine, formerly known as the Hammond, there is provided a type carrier or shuttle which may be operated, to select any desired type thereon, by means actuated by the key-levers; the actuatable means being arrested by settable devices also operable by the key-levers.

The actuation of a hammer is subsequently effected to co-operate with the selected type to print the character on a work-sheet. The means operable by the key-levers to set the type shuttle includes a universal bar engaged directly by the key-levers, and an arm extending therefrom to operate an actuator connected with the type shuttle. The actuator is arrested in various positions to accurately position the selected type at the printing point, and the actuation of the hammer is then effected to print on the work-sheet.

Since the printing takes place subsequently to arresting the shuttle actuator and because the key-lever is effective to hold said shuttle actuator against the arresting means through the medium of intermediate mechanism including the universal bar, it is necessary to strain the universal bar at each printing operation to effect the actuation of the printing hammer. This strain not only makes the machine hard to operate but after some usage causes a permanent set of the universal bar which throws the machine out of adjustment.

An object of the present invention is to provide a resilient connection between the key-levers and the type shuttle so that after the shuttle actuator has been arrested, a further movement of the active key-lever is facilitated, with a minimum of pressure on the key, to effect the actuation of the carriage escapement mechanism and the printing hammer.

In carrying out the invention in the form herein illustrated, the arm which extends from the universal bar to the type shuttle actuator is made resilient so that it may yield to permit a further actuation of the universal bar by the key-lever after the shuttle actuating arm has been arrested, to effect the printing operation of the hammer.

Other features and advantages will hereinafter appear.

In the accompanying drawings,

Fig. 1 is a sectional side view of the machine showing the invention applied thereto;

Fig. 2 is a detail sectional view taken on the line 2—2 of Fig. 1;

Fig. 3 is a fragmentary top plan view showing the shuttle actuating mechanism and the arresting means therefor; and

Fig. 4 is a sectional top plan view taken on the line 4—4 of Fig. 1.

Similar reference characters represent similar parts throughout the several views.

The machine includes a main frame 10, having a track 11 upon which a carriage 12 is arranged to travel back and forth through the medium of anti-friction rollers or balls 13 co-operating with the rail 11 and a bar 14 of said carriage. The carriage 12 may be guided at its upper end by means including a roller 15 and a guard 16 engaging a bar 17 on the carriage.

The carriage is urged in a letter space direction by means including a spring drum, not shown, connected to said carriage by a strap 18. The letter-space movements of the carriage are effected by escapement mechanism, indicated generally by the numeral 19, which is actuated at each operation of the key-levers 20.

The escapement 19 is of the usual Vari typer construction and is similar to that disclosed in the Sears Patent No. 644,188. It includes an escapement wheel 21 secured to a shaft 22 supported on the main frame 10. A rack 23 on the carriage 12 engages a pinion 24 connected to the escapement wheel 21 to rotate the latter upon each actuation of a dog rocker 25 pivoted at 26 on the machine frame 10 and effective to actuate a dog 27 thereon and a dog 28 supported on a pivoted frame 29.

To actuate the escapement mechanism 19 and thus feed the carriage at each type stroke. Each key-lever 20 is provided with a contact portion 20^a which, when the key-lever is actuated about a fulcrum 30, engages a universal bar 31 of a frame 32 to swing the latter about a fulcrum 33. An arm 34 of the frame, when the latter is actuated, swings downwardly, engages a tail 26^a of the dog rocker 25 to actuate the latter to carry the dog 27 into engagement with the escapement wheel 21, the dog rocker being connected to the dog 28 in the usual way to swing it about its pivot 35 out of engagement with the escapement wheel. To procure the proper engaging relation between the arm, tail 26^a of the dog rocker and the arm 34, the latter is provided with adjustable contact portions or screws 34^a and 34^b.

Upon the return of the actuated key-lever 20 the escapement devices are returned to normal in the usual manner thus effecting a letter space movement of the carriage; the motion of the

dog rocker being limited in both directions by adjustable stops 36 and 37.

The printing instrumentalities include a type carrier or shuttle 40, operable in a manner hereinafter described, to select any desired type 41 to be printed on a work sheet 42 supported by feed rollers 43 and 44 of a carriage 12. A hammer 45 at the opposite face of the work sheet co-operates with the types 41 to print on said work sheet. Said hammer may be swung about a pivot 46 by the action of a spring 47, but is normally held in its ineffective position by the frame 29 of the escapement mechanism, to which frame the hammer is connected by a stud 48.

15 The type shuttle 40 is supported through the medium of a fin-like member 50 thereon, extending through a slot 51 of an anvil 52 supported on a vertical shaft 52^a supported in a bar 53 and a plate 55 secured to the main frame 20 10.

To actuate the type shuttle 40 the fin 50 has connected thereto a lever 54 secured to a sleeve 56 to rotate about the shaft 52^a; the sleeve being supported on the bar 53 on which it is maintained by a screw 57 which engages a flange 56^a at the lower end of the said sleeve.

The shuttle actuating lever 54 may be actuated in opposite directions (Fig. 3) by arms 58 and 58^a, about the shaft 52^a; the arms being actuated, one at a time, in a manner hereinafter described to carry the selected type of the shuttle 40 to the printing point. Subsequently the hammer 45 is actuated as above described to co-operate with the selected type to print on the 35 work sheet.

The arms 58 and 58^a, which operate the shuttle actuating lever 54, form parts of frames 59 and 59^a supported to swing about pivots 60 and 60^a on fixed brackets 61 and 61^a. The frames 59 40 and 59^a also include bars 62 and 62^a extending to the middle of the machine and over the key-levers 20 (Figs. 1 and 4), so that if any one of the key-levers to the right of the middle of the machine is actuated it engages the bar 62 to 45 swing the frame 59 against the action of a return spring 63 to swing the upper end of the arm 58 rearwardly in Fig. 1 and thus actuate the lever 54 and shuttle 40 in a counter-clockwise direction (Fig. 3). Similarly the arm 58^a may 50 be actuated by any one of the group of key-levers to the left of the middle of the machine to actuate the type shuttle in the opposite direction.

The arms 58 and 58^a are provided at their upper ends with pin-like extensions 64 and 64^a respectively, which engage shoulders 65 and 65^a respectively, to operate the shuttle actuating lever 54 in opposite direction. Clearance slots 66 and 66^a are provided to prevent obstruction of the lever 54 by one of the pins 64 or 64^a while 60 said lever is being actuated by the other one of said pins.

To accurately position the selected type at the printing point the shuttle actuating lever 54 is provided with an arm 67^a which may engage 65 the upper end of any one of a plurality of stop pins 67 supported in an upper guide plate 68 and the lower guide plate 55. There is one stop rod 67 disposed above each key-lever 20 so that when one of the key-levers is depressed the corresponding stop rod is moved upwardly, against the action of a spring 69, to project its upper end into the path of the arm 67^a so as to arrest said arm, to position the selected type at the printing point.

It will be remembered that the printing hammer is actuated after the selected type is at the

printing point, and that its actuation is dependent upon the escapement mechanism 19; the latter being operable by the key-levers 20 through the medium of the frame 32 carrying the universal bar 31.

I have made provision of means whereby further actuation of the key-levers is facilitated after the shuttle actuating lever 54 has been arrested by one of the pins 67 so that the escapement 19 may be actuated with a minimum of effort. To this end I provide in the present form of the invention, a resilient connection between the arm 58 and the frame 59. The arm 58 is pivotally supported on a shoulder screw 70 threaded into an arm 71 of said frame. The arm 71 is provided with a stop 72 against which the arm 58 is normally held by a spring 73, in a housing 74 on the arm 71; one end of said spring pressing against a plunger 75 which bears against the edge of the arm 58; the other end of the spring bearing against a screw 76 by which it may be adjusted so that its pressure is great enough to prevent yielding of the arm 58 until the shuttle actuating lever is arrested by one of the stop rods 67. A nut 77 is provided to lock the spring adjusting screw 76 in its set position.

The stop 72 is in the nature of a set screw threaded into an ear 78 of the arm 71, and whereby the upper end of each arm 58 and 58^a may be adjusted relatively to the shoulders 65 and 65^a of the actuating lever 54.

It will be understood that the frame 58^a includes parts like those of the frame 58 and that these parts bear the same reference characters with the superscript *a*. It will further be understood that by providing each of the springs associated with the arms 58 and 58^a with adjusting means the touch of both sets of key levers may be kept equal or uniform in case the springs in themselves are of unequal strength.

It will be remembered that the operation of the escapement is effected after the type shuttle is arrested, and that heretofore the intermediate means between the key-lever and the shuttle operating lever 54 had to be strained in order to effect the actuation of the escapement. Thus it will readily be understood that a fine adjustment of the screw 34^a was required to cause the escapement to function at the proper time. It will be understood that this fine adjustment of 125 approximately $\frac{1}{4}$ turn of the screw (.005 of an inch) made a decided difference in the touch of the key-levers; this adjustment changing the touch from light to heavy. It will also be understood that due to this fine adjustment it was necessary to file the contact portions 20^a of the key-levers 20 to cause the escapement to function at the proper time.

With my improved form of resilient means, between the key-levers 20 and the shuttle actuating arm 54, the adjustment of the screw 34^a may have a range of $1\frac{1}{2}$ turns without a noticeable changing of the touch of the key-levers. Due to this increased adjustment of the screw 34 afforded by my improved means, the former need of filing of the contact faces of the key-levers is eliminated.

Having thus described the invention it should be understood that it is not to be limited to the specific embodiment illustrated herein, there being variations of the invention which fall within the scope of the appended claims.

I claim:

1. In a typewriting machine, the combination of a type shuttle, a hammer to co-operate therewith,

a horizontally disposed lever to actuate the shuttle, a pivot having a vertical axis about which said lever may be operated, key-levers, a universal bar operable by the key-levers, an arm extending 5 upwardly from the universal bar, a pivot for the universal bar having a horizontal axis, the upper end of the arm engaging the shuttle lever, a spring on the universal bar to press against said arm to cause the latter to move with the universal 10 bar when actuated, means to arrest the shuttle lever to register the selected type at the printing point, said spring permitting a further actuation of the universal bar independently of the universal bar after the shuttle lever has been arrested 15 to permit a further operation of the key-

levers, and means operable by the key-levers during such further actuation to effect the actuation of said hammer.

2. In a typewriting machine, the combination of a type carrier, a pivoted actuating element for said carrier, key levers, a universal bar frame operable by said key levers and including a rigid upwardly extending arm, a pivoted arm supported by the rigid arm, a housing on said rigid arm, a stop on said rigid arm, a spring in said housing and pressing said pivoted arm against said stop, means to permit an adjustment of said stop, and an adjustable screw in one end of said housing to adjust said spring. 80 85
